COMBINATION GOGGLES AND HEADBAND

Jerry R. Gould, Gunnison, Ga.
(2200 N. 9th Laramie, Wyo. 82070)

Filed Sept. 24, 1965, Ser. No. 87,158

Term of patent 14 years

(Cl. D57—1)

The rear of the goggles not shown conforms substantially in configuration to the front shown in FIGURE 2.

The broken line showing in FIGURE 1 is for illustrative purposes only.

I claim:

The ornamental design for combination goggles and headband, as shown and described.
